(57) **CLAIM**

The ornamental design for a ceiling panel, as shown and described.

DESCRIPTION

FIG. 1 is a front-right top perspective view of a ceiling panel according to a first embodiment of our new design; FIG. 2 is a front-right bottom perspective view of the ceiling panel thereof; FIG. 3 is a rear-left top perspective view of the ceiling panel thereof; FIG. 4 is a rear-left bottom perspective view of the ceiling panel thereof; FIG. 5 is a front elevational view of the ceiling panel thereof; FIG. 6 is a rear elevational view of the ceiling panel thereof; FIG. 7 is a top plan view of the ceiling panel thereof; FIG. 8 is a bottom plan view of the ceiling panel thereof; FIG. 9 is a right-side elevational view of the ceiling panel thereof; FIG. 10 is a left-side elevational view of the ceiling panel thereof; FIG. 11 is a front-right top perspective view of a ceiling panel according to a second embodiment of our new design; FIG. 12 is a front-right bottom perspective view of the ceiling panel thereof; FIG. 13 is a rear-left top perspective view of the ceiling panel thereof; FIG. 14 is a rear-left bottom perspective view of the ceiling panel thereof; FIG. 15 is a front elevational view of the ceiling panel thereof; FIG. 16 is a rear elevational view of the ceiling panel thereof; FIG. 17 is a top plan view of the ceiling panel thereof; FIG. 18 is a bottom plan view of the ceiling panel thereof;

(Continued)

FIG. 224 is a rear-left bottom perspective view of the ceiling panel thereof;
 FIG. 225 is a front elevational view of the ceiling panel thereof;
 FIG. 226 is a rear elevational view of the ceiling panel thereof;
 FIG. 227 is a top plan view of the ceiling panel thereof;
 FIG. 228 is a bottom plan view of the ceiling panel thereof;
 FIG. 229 is a right-side elevational view of the ceiling panel thereof;
 FIG. 230 is a left-side elevational view of the ceiling panel thereof;
 FIG. 231 is a front-right top perspective view of a ceiling panel according to a twenty-fourth embodiment of our new design;
 FIG. 232 is a front-right bottom perspective view of the ceiling panel thereof;
 FIG. 233 is a rear-left top perspective view of the ceiling panel thereof;
 FIG. 234 is a rear-left bottom perspective view of the ceiling panel thereof;
 FIG. 235 is a front elevational view of the ceiling panel thereof;
 FIG. 236 is a rear elevational view of the ceiling panel thereof;
 FIG. 237 is a top plan view of the ceiling panel thereof;
 FIG. 238 is a bottom plan view of the ceiling panel thereof;
 FIG. 239 is a right-side elevational view of the ceiling panel thereof;
 FIG. 240 is a left-side elevational view of the ceiling panel thereof;
 FIG. 241 is a front-right top perspective view of a ceiling panel according to a twenty-fifth embodiment of our new design;
 FIG. 242 is a front-right bottom perspective view of the ceiling panel thereof;
 FIG. 243 is a rear-left top perspective view of the ceiling panel thereof;
 FIG. 244 is a rear-left bottom perspective view of the ceiling panel thereof;
 FIG. 245 is a front elevational view of the ceiling panel thereof;
 FIG. 246 is a rear elevational view of the ceiling panel thereof;
 FIG. 247 is a top plan view of the ceiling panel thereof;
 FIG. 248 is a bottom plan view of the ceiling panel thereof;
 FIG. 249 is a right-side elevational view of the ceiling panel thereof;
 FIG. 250 is a left-side elevational view of the ceiling panel thereof;
 FIG. 251 is a front-right top perspective view of a ceiling panel according to a twenty-sixth embodiment of our new design;
 FIG. 252 is a front-right bottom perspective view of the ceiling panel thereof;
 FIG. 253 is a rear-left top perspective view of the ceiling panel thereof;
 FIG. 254 is a rear-left bottom perspective view of the ceiling panel thereof;
 FIG. 255 is a front elevational view of the ceiling panel thereof;
 FIG. 256 is a rear elevational view of the ceiling panel thereof;
 FIG. 257 is a top plan view of the ceiling panel thereof;
 FIG. 258 is a bottom plan view of the ceiling panel thereof;

FIG. 259 is a right-side elevational view of the ceiling panel thereof;
 FIG. 260 is a left-side elevational view of the ceiling panel thereof;
 FIG. 261 is a front-right top perspective view of a ceiling panel according to a twenty-seventh embodiment of our new design;
 FIG. 262 is a front-right bottom perspective view of the ceiling panel thereof;
 FIG. 263 is a rear-left top perspective view of the ceiling panel thereof;
 FIG. 264 is a rear-left bottom perspective view of the ceiling panel thereof;
 FIG. 265 is a front elevational view of the ceiling panel thereof;
 FIG. 266 is a rear elevational view of the ceiling panel thereof;
 FIG. 267 is a top plan view of the ceiling panel thereof;
 FIG. 268 is a bottom plan view of the ceiling panel thereof;
 FIG. 269 is a right-side elevational view of the ceiling panel thereof;
 FIG. 270 is a left-side elevational view of the ceiling panel thereof;
 FIG. 271 is a front-right top perspective view of a ceiling panel according to a twenty-eighth embodiment of our new design;
 FIG. 272 is a front-right bottom perspective view of the ceiling panel thereof;
 FIG. 273 is a rear-left top perspective view of the ceiling panel thereof;
 FIG. 274 is a rear-left bottom perspective view of the ceiling panel thereof;
 FIG. 275 is a front elevational view of the ceiling panel thereof;
 FIG. 276 is a rear elevational view of the ceiling panel thereof;
 FIG. 277 is a top plan view of the ceiling panel thereof;
 FIG. 278 is a bottom plan view of the ceiling panel thereof;
 FIG. 279 is a right-side elevational view of the ceiling panel thereof; and,
 FIG. 280 is a left-side elevational view of the ceiling panel thereof.
